UNITED STATES PATENT OFFICE.

EMIL H. RONAY, OF BROOKLYN, NEW YORK, ASSIGNOR TO R. M. HAAN CANDY CO., INC.,
OF NEW YORK, N. Y., A CORPORATION OF NEW YORK.

DESIGN FOR A BOX.

Application filed February 4, 1928 Serial No. 25,194. Term of patent 14 years.

To all whom it may concern:

Be it known that I, EMIL H. RONAY, a citizen of the United States, residing at Brooklyn, county of Kings, and State of New York, have invented a new, original, and ornamental Design for a Box, of which the following is a specification, reference being had to the accompanying drawings, forming part thereof.

The fragmentary marginal ornamentation shown in the figures continues around the entire periphery.

I claim as my invention:

The ornamental design for a box substantially as shown and described.

EMIL H. RONAY.
